UNITED STATES PATENT OFFICE.

JENNIE L. P. FEINSTEIN, OF GRAND FORKS, NORTH DAKOTA.

CHILD'S UNDERGARMENT.

1,225,945.

Specification of Letters Patent. Patented May 15, 1917.

Application filed March 23, 1916. Serial No. 86,119.

To all whom it may concern:

Be it known that I, JENNIE L. P. FEINSTEIN, a citizen of the United States, residing at Grand Forks, county of Grand Forks, 5 and State of North Dakota, have invented certain new and useful Improvements in Children's Undergarments, of which the following is a specification.

This invention relates to children's undergarments.

It has heretofore been a common practice to support a child's petticoat, drawers and stockings from an undervest, necessitating an additional article of clothing.

15 My object is to dispense with the skeleton or cloth vest heretofore commonly used for this purpose and to provide an improved undergarment having improved means for supporting the stockings and petticoat when 20 the invention is embodied in a union suit, and also supporting the drawers when it is embodied in an undershirt, thus relieving the weight and strain on the child's shoulders incident to the use of a vest and more 25 evenly distributing the weight and strain so that greater comfort will be obtained.

The embodiments of the invention which are hereinafter set forth and disclosed in the accompanying drawings are to be considered 30 as illustrative, rather than restrictive, of the scope of the invention, which is susceptible of modification.

In the accompanying drawings:

Figure 1 is a front view showing the invention embodied in a knit union undergarment;

Fig. 2, a similar view of the invention embodied in a knit undershirt;

Fig. 3, a detail of a part of Fig. 1;

40 Fig. 4, a horizontal detail section of the multi-knit band and its attachments;

Fig. 5, a detail vertical section of the multi-knit band, showing a button and reinforcement therefor; and

45 Fig. 6, a detail of a part of the knit band of the garment of Fig. 1, the stocking supporter being removed.

My invention has probably its greatest utility in its embodiment in a knit union 50 suit, as shown in Fig. 1, because the necessity for separate drawers and their attachment to the multi-knit band is obviated, but the invention can be just as well carried out in a knit undershirt, such as shown in Fig. 55 2, it only being necessary to add additional

buttons to the knit band for the attachment of the separate drawers, not shown, which are then necessary.

Referring first to Fig. 1, the union suit 1 is of knit material throughout and it may have any kind of a full-drop, or, semi-drop seat, not shown, and provided with any ordinary or preferred front opening 2. One part of my invention is obtained by the provision of a thickened, strengthened, knit belt 3 which is an integral or homogeneous part of the garment.

The thickened belt 3^a of the knit shirt 1^a of Fig. 2 is in all respects similar to the knit belt 3. The belt or band 3 is preferably 70 triple knit, or, it may have any desired number of layers or knittings 4, as shown in Fig. 5, and the knitting may be of any ordinary or preferred kind. The purpose of this band or belt is not to afford elasticity or 75 yielding such as has been heretofore commonly employed in union suits to relieve strain when the wearer is in a stooping posture and to afford greater comfort at the crotch, but on the contrary, belt 3 is composed of a plurality of knittings or layers for the purpose of added strength and to minimize yielding or stretching and to afford a suitable supporting band for the petticoat, stockings and, when embodied in 80 a shirt as in Fig. 2, also the drawers.

The belt 3 extends all the way around the garment whether a union garment, as in Fig. 1, or an undershirt, as in Fig. 2, but, in any event, where the front opening 2 should cross the band, the latter is left open or non-continuous at 5, which would be the case in a union suit and might, or might not, be true of an undershirt.

For the support of the petticoat I provide 95 any suitable number of buttons 6, so that the petticoat may be directly buttoned to the multi-knit belt 3, or 3^a. These buttons may be directly connected to the belt 3, but they are preferably stitched through the belt to a 100 reinforcing piece of fabric 7, as shown more clearly in Fig. 4 to avoid injury to the belt.

Where the invention is carried out in a shirt, I also provide lower buttons 8 at the front and rear of the belt for the detachable 105 connection of the drawers, as shown in Fig. 2. These will also be reinforced by attachment to pieces of fabric corresponding to the fabric 7. Either separate pieces of fabric 7 or a continuous tape may be used 110.

as the reinforcing medium and, while the tape is not disclosed, it is to be considered within the scope and spirit of the invention.

At suitable points the belt 3 is provided with eyelets 9 which may be either worked in the belt or be of metal, the latter form being shown. My invention comprehends both forms, but metal eyelets are preferred as they will better withstand the strain and wear. Whether of metal, or worked, there is provided a protective piece of fabric 10 on the inside of the belt 3, to interpose a shield between the body of the wearer and the inner faces of the eyelets. The protective piece 10 is stitched at 11 to the belt 3 and the intermediate parts of the piece 10 are free so that the safety-pins 12 which are used to suspend the stocking supporters 13 may be easily inserted through the eyelets without the points of the pins puncturing the body of the wearer, and when in use, the protective pieces 10 prevent abrasion of the skin. The stocking supporters 13 are permanently carried by the fixed parts of the safety-pins 12 at 14. To detach the stockings, it is only necessary to unclasp the safety-pins and slip them out of the eyelets 9, thus entirely obviating the necessity of opening the usual stocking clasps 15, much time being thus saved in putting on or removing the stockings. The petticoat and the drawers, if used with a shirt alone, may be readily buttoned to or unbuttoned from the belt 3.

With my improvements, the strain which has heretofore been placed solely on the child's shoulders, due to the employment of an undervest, is partly borne by the shoulders and partly by the body, rendering wearing of the garment more comfortable, which is due in some measure to the elasticity of the body and drawer portions of the union suit of Fig. 1, or the body and skirt of the shirt of Fig. 2. While it is possible that the belt 3 may have some elasticity, this is incidental to the knit construction thereof and triple knitting during the manufacture of the garment is provided to strengthen, solidify and prevent stretching of the belt so that it will be adapted to retain its shape and will afford a firm support for the undergarments.

Having thus described my invention, what I claim as new and desire to secure by Letters Patent, is:—

1. A knit undergarment having a belt integrally knit therewith provided with eyelets adapted to receive fastening devices for garment supporters.
2. A knit undergarment having a belt integrally knit therewith provided with eyelets adapted to receive fastening devices for garment supporters and a reinforcing piece connected to the belt behind the eyelets and provided with an intermediate free portion.

In testimony whereof, I hereunto affix my signature.

JENNIE L. P. FEINSTEIN.
